UNITED STATES PATENT OFFICE

162,509

ELECTRICAL OUTLET BOX COVER

Merritt B. Austin, Jr., Deerfield, Ill.

Application October 17, 1950, Serial No. 12,605

Term of patent 14 years

(Cl. D26—1)

To all whom it may concern:

Be it known that I, Merritt B. Austin, Jr., a citizen of the United States, residing at Deerfield, county of Lake, and State of Illinois, have invented a new, original, and ornamental Design for an Electrical Outlet Box Cover, of which the following is a specification, reference being had to the accompanying drawings, forming part thereof.

Fig. 2 is a top plan view of the same.

Fig. 3 is a side elevation of the same.

I claim:

The ornamental design for an electrical outlet box cover, as shown.

MERRITT B. AUSTIN, JR.
